WELL FLOWING DEVICE

Lester D. Mowrey, Wichita Falls, Tex.

Application February 21, 1940, Serial No. 320,210

12 Claims. (Cl. 103—232)

This invention relates to an apparatus for elevating liquids from a lower level to a higher level, and more particularly to the lifting of water or oil in wells by air or gas pressure.

The present invention is an improvement on that set forth in my prior co-pending application for Gas lift flow devices, Serial No. 278,530, filed June 10, 1939.

In oil fields there is a certain amount of gas associated with or entrapped in the liquid oil when the reservoir is first penetrated. This gas functions to lift the oil while the well is on natural flow. After the well ceases to flow naturally, there is almost as much gas per barrel accompanying the oil from the formation as when the well was flowing naturally, but the reservoir pressure has declined until the gas is insufficient to continue the lifting operation. Under these circumstances it is necessary that some means be provided to lift the oil in the well.

Various types of gas pressure lifts have been employed, using both open and closed end floats, but these have depended upon the buoyancy of the float to open a gas or air inlet valve so as to aerate the liquid to cause it to rise within the tubing.

In this invention, the opposite principle is utilized, i. e., as long as the float has a buoyancy greater than that of the displacement of the liquid, it will have a tendency to rise and close the valve. As long as the liquid does not exert a hydrostatic pressure on the float to such an extent as to compress the air or gas within the float and the weight of the float is less than the weight of the liquid which it displaces, the float will hold the valve closed. However, when this buoyancy decreases to the extent of being less than the buoyancy of the liquid displaced, the float will sink, permitting the valve to open and introduce gas or air into the tubing containing the liquid so as to aerate the liquid and move it upward in the tubing.

This action is entirely automatic in operation, i. e., when predetermined hydrostatic pressure accumulates within the tubing, the apparatus will function, thereby causing the float operated valve to open and discharge a portion of the liquid upward through the tubing under the force of gas introduced from a point exteriorly of the tubing. Due to the fact that this valve arrangement retains the natural reservoir pressure by preventing the waste of gas or air, less additional gas or air will be necessary than would be required otherwise to lift the liquid in the well.

This invention is an improvement on that set forth in my co-pending application hereinbefore mentioned, inasmuch as I have here provided for keeping the float chamber filled at all times with liquid, thereby excluding substantially all foreign matter from close contact with the operating mechanism and insuring the continued presence of sufficient liquid in the float chamber to operate the float. By having a float chamber always filled with liquid, the control valve will remain closed even if the pressure in the well should blow liquid therefrom or if the level of liquid should fall below the flow unit. The float is responsive to a pressure exerted by a column of fluid above the float and is not responsive to gas pressure in the casing.

A preferred embodiment of this invention is illustrated in the accompanying drawing, in which—

20 Fig. 1 is a vertical sectional view through a well showing a plurality of flow units comprising the invention, installed therein;

Fig. 2 is an enlarged vertical section of the upper portion of the flow unit and valve mechanism;

Fig. 3 is similar view of the lower portion of the flow unit, showing the check valve installed in the bottom thereof;

Fig. 4 is a horizontal section taken on the line 30 4—4 of Fig. 2, looking in the direction of the arrows;

Fig. 5 is a horizontal section taken on the line 5—5 of Fig. 2, looking in the direction of the arrows; and

35 Fig. 6 is a horizontal section taken on the line 6—6 of Fig. 3, looking in the direction of the arrows.

In the drawing, the numeral 1 designates the casing of a conventional deep well having a casing head 2 at its upper end thereof, which casing head is sealed by a cap 3 to prevent escape of pressure from the well.

Within the well casing 1 is disposed a tubing 4 that extends to a point adjacent the bottom of the well and has the usual perforated pipe 5 on the end thereof.

Flow units 6 may be mounted at spaced intervals in the tubing 4, the number used depending upon the depth and capacity of the well, a sufficient number being employed to effect step by step upward flow of liquid to the top of the well.

Each flow unit 6 comprises a tubular member 7 having a head 8 at the upper end thereof and a bottom member 9 attached to lower end thereof and respectively closing said tubular member at

the opposite ends thereof. The head 8 and the bottom member 9 are bored and screw threaded to receive the adjacent ends of sections of the flow tubing 4.

Mounted within the tubular member 7 between the head 8 and bottom member 9 is a central float chamber 10. The space between the chamber 10 and the tubular member 7 provides an annular flow chamber 11 through which flows the liquid rising in the well.

The float chamber 10 has a partition plate 12 closing the lower end thereof, whereby the chamber 10 is adapted to hold a quantity of liquid at all times for a purpose later to be more fully explained. Below the partition plate 12 is an inlet chamber 13 having discharge openings 14 through the sides thereof into the annular flow chamber for the purpose of directing liquid from the flow tubing 4 into the annular chamber 11. The inlet chamber 13 is normally closed at the bottom by a check valve 15. The check valve 15 has a normal tendency to close under a weak spring tension but the upward pressure of rising fluid readily opens the valve, the function of which is to prevent a "back flow" or "back wash" down the tubing 4 to the producing formation during the aerating periods. The valves also serve to hold all liquid that passes above the valves when they are used in series. Fluid communication between the flow chamber 11 and the central float chamber 10 is provided through orifices 16 at the upper end of the chamber 10. The annular flow chamber 11 also communicates with the upper section of tubing 4 through ducts 17 in the head 8.

Thus liquid from the well may pass up through the lower section of flow tubing 4, through the openings 14, into the flow chamber 11, and upward through the ducts 17, to the upper section to flow tubing 4 through which it passes as far as the reservoir pressure will carry it until the liquid head becomes static. As the liquid passes upward by the orifices 16, the central chamber 10 will be maintained filled with liquid so as to insure the float the proper working liquid and to impart the pressure of the hydrostatic head to the float.

For the purpose of aerating the liquid to assist in raising it from the well, an automatic float mechanism is provided to admit air or gas thereto which float mechanism operates when the pressure of the hydrostatic head reaches a predetermined point. This float mechanism is mounted within the central chamber 10 and is operatively connected with a valve 18 which controls the flow of gas into the chamber 10 through an inlet duct 19 formed in the head 8 and which duct 19 communicates at its opposite end with the exterior of the flow unit 6 within the well casing 1. The gas admitted past valve 18 into chamber 10 escapes through orifices 16, aerating the column of static liquid thereabove, causing it to flow upward in the tubing 4.

The float mechanism for operating the valve 18 comprises an operating lever 20 pivotally mounted at 21 on a dependent bracket 22 suspended from the head 8 within the chamber 10. The lever 20 underlies the stem of the valve 18 in position for moving said valve to a seated position. The operating lever 20 has integrally formed therewith an arm 23 which extends downwardly through the float chamber 7 and has an offset portion 24 at its lower end in position for engagement by a roller 25. The roller 25 is journaled on a lever 26 pivotally attached at 27 to

the dependent bracket 22. A link 28 suspends a float 29 from the free end of the lever 26. A rest 30 is provided at the bottom of the dependent bracket for limiting the downward swinging movement of lever 26. The float 29 comprises a hollow cylindrical tube closed at its upper end and open at the lower end thereof. The float 29 is provided with peripheral projections 31 on the sides thereof for guiding the upward and downward movements of the float in the chamber 10.

A plug 32 is provided in the connecting head 8 whereby the float chamber 10 may be filled with liquid prior to insertion of the flow unit into the well, which, under normal atmospheric pressure, will cause the float 29 to rise in the chamber and close the valve 18. By filling the chamber with a clean liquid prior to placing in the well, very little foreign matter will find its way into the chamber through orifices 16, as very little additional liquid will pass into the chamber during the operation thereof.

In operation, the upper portion of the enclosed well casing 1 will be filled with entrapped air or gas under pressure, and as the liquid rises in the well casing it will pass through the perforated pipe 5 and the lowest section of the tubing 4, thence past the check valve 15, through holes 14 and into the flow chamber 11, thence upwardly through ducts 17 into the upper section of the tubing 4. The liquid continues to pass up through the tubing 4 until it becomes static due to the equalization of pressure.

When the liquid rises to a sufficient height above the level of the orifices 16 in the float chamber 10, a pressure will be exerted on the liquid contained therein causing a compression of the air or gas trapped within the upper end of the float 29. When the compression of the entrapped air or gas reaches that point at which the liquid displacement of the float is less than the weight thereof, the float moves downward in the liquid. As the float moves downwardly in the float chamber 10 the lever 29 swings downwardly allowing downward movement of the valve 18 which opens the passageway 19 and admitting air or gas under pressure into the upper end of the float chamber 10 above the liquid therein, which air or gas passes outwardly through orifices 16 and upwardly through said tubing 4.

It is, of course, understood that the weight of the float assembly, without the entrapped gas, is greater than the weight of the liquid which it displaces, and the height of the column of oil is dependent upon the amount of pressure required to sink the float. These factors determine the points at which the aerating valve opens and closes.

Air or gas may also be introduced on the outside at the upper end of the casing 1 in order to furnish any additional pressure required. A supply pipe is indicated at 33 in Fig. 1 of the drawing for the admission of such gas under pressure to the casing 1, if desired.

By the use of this gas lift flow device, the flowing pressure can be governed by the hydrostatic head in the tubing to give maximum efficiency. By closing the casing at the top and holding the reservoir pressure within the casing, the reservoir pressure can be utilized for flowing after it has declined below the point where the well will flow naturally. This pressure will elevate the liquid in the flow tubing to a point where the gas lift flow device may be installed to utilize the reservoir pressure to lift the liquid to the surface, either directly or by stages. If necessary, a series

of these devices may be installed, as shown in Fig. 1 of the drawing.

When a series of flow units are installed, a hydrostatic head is built up above a second of the additional flow units, and the same operation will occur as has just been described, each unit giving additional aeration to the liquid. With the present device the second or additional flow units will not allow any escape of gas pressure until successive hydrostatic heads are built up above the flow units in turn.

A further advantage to be gained by using a float as described herein is that this float will not collapse under pressure as the pressure is always equal inside and outside at any point on the float.

It will be noted that in the operation of the device, the casing or lifting pressure has nothing to do with the automatic control of the device, as it is controlled by the hydrostatic pressure within the float chamber. Therefore, the casing or lifting pressure can have a wide variance without affecting the operation of the device.

I claim:

1. In a flow device, a chamber having an inlet and an outlet adapted for flow of liquid therethrough, a second chamber adjacent the first-mentioned chamber having a fluid passage connecting the same with the first-mentioned chamber, the liquid inlet of the first-mentioned chamber being arranged out of communication with the second-mentioned chamber, said second chamber having a fluid inlet, and means for controlling said fluid inlet, said controlling means being constructed for trapping compressible fluid therein with said compressible fluid in communication with the liquid in said second chamber, said liquid outlet of the first-mentioned chamber being separate from the second chamber for discharging the liquid from the first-mentioned chamber independently of the second chamber.

2. In a flow device, a chamber having an inlet and an outlet adapted for flow of liquid therethrough, a second chamber adjacent the first-mentioned chamber having a fluid passage connecting the same with the first-mentioned chamber, said second chamber having a fluid inlet, and means movably mounted in said second chamber for controlling said fluid inlet, said controlling means being constructed for trapping compressible fluid therein with said compressible fluid in communication with the liquid in said second chamber and movable in response to the compression thereof by hydrostatic pressure of the liquid to permit opening movement of the inlet controlling means, said liquid outlet of the first-mentioned chamber being separate from the second chamber for discharging the liquid from the first-mentioned chamber independently of the second chamber.

3. In a flow device, a chamber adapted for flow of liquid therethrough, a second chamber enclosed within the first-mentioned chamber and having a fluid passage connecting the same with the first-mentioned chamber, said second chamber having a gaseous fluid inlet communicating with the exterior of said flow device, means for closing said fluid inlet, and means movably mounted in said second chamber and operatively connected with said inlet closing means, said movable means being constructed for trapping compressible fluid therein in open communication with the liquid contained in said second chamber and holding the inlet closed by fluid contained in said second chamber, said means

moving in response to the compression of the fluid by the hydrostatic pressure of the liquid thereon to permit opening of the fluid inlet.

4. In a flow device, a chamber adapted for flow of liquid therethrough, a second chamber mounted within said first-mentioned chamber and having communication with said outer chamber, said inner chamber being adapted to contain fluid and having a gas inlet communicating with the exterior of said flow device, a valve for controlling said gas inlet, and means mounted within said inner chamber for actuating the valve, said means being movable by the liquid contained in said inner chamber normally to hold the valve closed and having a compressible fluid therein, said means being movable in response to a compression of the fluid by the liquid in the inner chamber for permitting opening movement of the valve.

5. In a flow device, a chamber adapted for flow of liquid therethrough, a second chamber mounted within said first-mentioned chamber and having its upper end in open communication with the outer chamber, said inner chamber being closed at the lower portion whereby fluid is contained therein at all times, said inner chamber having a gas inlet communicating with the exterior of said flow device, a valve for controlling said gas inlet, and float means within said inner chamber for actuating the valve, said float means being movable by the liquid contained in said inner chamber normally to hold the valve closed and having a compressible fluid therein in communication with the inner chamber for compression by the hydrostatic pressure of the liquid.

6. In a flow device, a chamber adapted for flow of liquid therethrough, a second chamber mounted within said first-mentioned chamber and having its upper end in open communication with the outer chamber, said inner chamber being closed at the lower portion thereof whereby liquid is adapted to be contained therein, said inner chamber having a gas inlet communicating with the exterior of said flow device, a valve for controlling said gas inlet, and float means within said inner chamber for actuating the valve, said float means being movable by the liquid contained in said inner chamber normally to hold the valve closed and having a compressible fluid therein in communication with the inner chamber for compression by the hydrostatic pressure of the liquid, said float means being movable in response to a compression of the fluid for permitting opening of the valve.

7. In a flow device, a chamber adapted for flow of liquid therethrough, a second chamber mounted within said first-mentioned chamber and having its upper end in open communication with the outlet chamber, said inner chamber having the lower portion thereof closed whereby liquid is contained therein at all times, said inner chamber having a gas inlet communicating with the exterior of said flow device, a valve for controlling said gas inlet, and a float in said inner chamber operatively connected with said valve for actuating the same and in position for movement by the liquid in the chamber normally to hold the valve closed, said float comprising a chamber with its upper portion closed and its lower portion in communication with the said inner chamber in position to trap compressible fluid therein by the liquid, said float being constructed for movement upon compression of the fluid by the hydrostatic pressure of the liquid to permit opening of the valve.

8. In a flow device, the combination of a casing, flow tubing therein, means for confining gas under pressure in the casing around the tubing, a chamber in the casing connected with the tubing and adapted for flow of liquid therethrough, a second chamber mounted within said first-mentioned chamber and having its upper end in open communication with the outer chamber, said inner chamber having the lower portion thereof closed whereby liquid is contained therein, means forming a gas inlet for admitting gas from the casing to the inner chamber, means for controlling said gas inlet, and means movable within the inner chamber for actuating said controlling means, said movable means being constructed for trapping compressible fluid therein for compression by the hydrostatic head of liquid in said flow tubing, said movable means being movable in response to a compression of the fluid for permitting opening of the inlet controlling means to admit gas to the inner chamber for passage therethrough to the outer chamber and flow tubing.

9. In a flow device, the combination of a casing, flow tubing therein, means for confining gas under pressure in the casing around the tubing, a chamber in the casing connected with the tubing and adapted for flow of liquid therethrough, a second chamber mounted within said first-mentioned chamber and having its upper end in open communication with the outer chamber, said inner chamber having the lower portion thereof closed whereby liquid is contained therein, means forming a gas inlet for admitting gas under pressure to the inner chamber, means for controlling said gas inlet, and float means within the inner chamber for actuating said controlling means, said float means being constructed for trapping compressible fluid therein in communication with the liquid in the chamber for compression by the hydrostatic head in the flow tubing, said float means being movable in response to compression of the fluid therein for permitting opening of the inlet controlling means to admit gas to the inner chamber for passage to the outer chamber and flow tubing.

10. In a flow device, a chamber adapted for flow of liquid therethrough, a second chamber having its upper end in communication with the first-mentioned chamber, said second chamber having the lower portion thereof closed whereby liquid

may be contained therein, said second chamber having a gas inlet communicating with the exterior of said flow device, a valve for controlling said gas inlet, and a float mounted within said second chamber enclosing a compressible fluid and so constructed and arranged as to permit operation of the valve at a predetermined loss in the buoyancy thereof, said gas inlet being located externally of the float and admitting gas to the second chamber outside of said float.

11. In a flow device, a chamber adapted for flow of liquid therethrough, a second chamber mounted within said first-mentioned chamber and having its upper end in open communication with the outer chamber, said inner chamber having the lower portion thereof closed whereby liquid may be contained therein, said inner chamber having a gas inlet communicating with the exterior of said flow device, a float mounted in said inner chamber and operatively connected with said valve normally to hold said valve in closed position, said float comprising a tube closed at its upper end and open at its lower end to allow entrance of a liquid head to entrap compressible fluid therein, said float being adapted to loose buoyancy as the pressure of the liquid head increases and compresses the fluid therein causing the float to drop at a predetermined pressure and permit said valve to open.

12. In a flow device, the combination of the casing, flow tubing therein, means for confining gas under pressure in the casing around the tubing, a chamber in the casing connected with the tubing adapted for flow of liquid therethrough, a second chamber mounted within said first-mentioned chamber and having its upper end in open communication with the outer chamber, said inner chamber having the lower portion thereof closed whereby liquid is contained therein, said flow unit having an inlet port connecting the interior of said inner chamber with the casing, a valve for controlling said inlet port, and means within said inner chamber for holding said valve normally closed until a predetermined pressure is applied to said means, said means comprising a float so constructed and arranged as to act to permit opening of said valve as the buoyancy of said float is decreased a predetermined amount by action of said predetermined pressure.

LESTER D. MOWREY.
